(57) CLAIM

The ornamental design for a narrow spaces duster, as shown and described.

DESCRIPTION

FIG. 1 is a front elevational view for a narrow space duster with the sleeve removed showing my new design, the rear being a mirror image; and,

FIG. 2 is a front elevational view of the narrow space duster; the rear being a mirror image.

The sides of the duster's sleeve and the sides of the wire frame not shown in the drawings or described in the specification form(s) no part of the claimed design.
